(57) **CLAIM**

The ornamental design for an aircraft clamp installation and removal holder, as shown and described.

DESCRIPTION

FIG. 1 is a perspective view of an aircraft clamp installation and removal holder showing my new design;

FIG. 2 is a top plan view thereof, the bottom being a mirror image thereof;

FIG. 3 is a left-side elevational view thereof;

FIG. 4 is a right-side elevational view thereof; and,

FIG. 5 is a front elevational view thereof, the rear being a mirror image thereof.
